UNITED STATES PATENT OFFICE.

ALBERT F. SCHROEDER, OF CLEVELAND, OHIO.

DESIGN FOR A HANDLE.

47,082.

Specification for Design.

Patented Mar. 9, 1915.

Application filed November 12, 1914. Serial No. 871,801. Term of patent 3½ years.

To all whom it may concern:

Be it known that I, ALBERT F. SCHROEDER, a citizen of the United States, residing at Cleveland, in the county of Cuyahoga and State of Ohio, have invented a new, original, and ornamental Design for Handles, of which the following is a specification, reference being had to the accompanying drawing, forming part thereof.

showing my new design. Fig. II is a side view of Fig. I. Fig. III is a rear elevation.

I claim:—

The ornamental design for a handle as shown.

ALBERT F. SCHROEDER.
